UNITED STATES PATENT OFFICE

HORACE F. GRUMAN, OF ST. LOUIS, MISSOURI, ASSIGNOR TO LEWIS INVISIBLE STITCH MACHINE COMPANY, OF KITTERY, MAINE, A CORPORATION OF MAINE

SEWING MACHINE

Application filed October 29, 1925. Serial No. 65,580.

This invention relates to sewing machines and more particularly such machines as may be used in the manufacture of special garments to sew special seams therefor.

5 In sewing certain kinds of material such for instance as knit goods, as in the manufacture of underwear, sweaters, bathing suits and the like, it is often desirable to cover the edge of the work after sewing a seam with an 10 over-stitch seam covering the trimmed edge so as to prevent unraveling and also to improve the appearance of the finished seam.

One of the objects of this invention is to provide a sewing machine on which such knit 15 goods may be operated upon and which will be capable of sewing in one operation both a plain seam for sewing two or more thicknesses of material together, and an over-stitch seam adapted to cover and protect the edge of the 20 work outside of the first seam.

Another object of this invention is to provide sewing mechanism which will be capable of sewing different kinds of seams simultaneously and which will operate by means of simple 25 mechanical movements.

Another object is to provide a machine in which a plurality of stitching mechanisms are so combined and coordinated as to simultaneously sew different seams.

30 Another object is to provide an improved stitching mechanism for over-stitching the edge of the work.

Further objects will appear from the following description taken in connection with 35 the accompanying drawings, in which:

Figure 1 is a vertical longitudinal section as seen from the front illustrating a sewing machine embodying this invention;

Figure 2 is a horizontal section of the same 40 taken about on line 2—2, Figure 1;

Figure 3 is a section on line 3—3, Figure 1;

Figure 4 is a section on line 4—4, Figure 1;

Figure 5 is a rear view of the machine;

Figure 6 is a detail of the looper mechanism 45 forming a part of the over-stitching mechanism;

Figure 7 is a detail of the driving mechanism for the two main loopers;

Figure 8 is a detail of the trimmer mech- 50 anism;

Figures 9, 10, and 11 are diagrammatical views illustrating the formation of the over-stitch;

Figure 12 is a diagrammatical view of the work illustrating the relations between the 55 different operations, and

Figure 13 is a cross section of the finished work.

Referring to the accompanying drawings 60 1 designates the base usually constructed of cast iron or similar material. The base 1 has mounted thereon a main casting or housing 2 which is adapted to enclose various moving parts and which is provided with a head 3.

65

Main driving connections

Mounted in bearings 4 in the main housing 2 is a main horizontal drive shaft 5. This shaft may have mounted thereon a driving 70 pulley 6 or other suitable means of connection to a suitable source of power not shown. Connected by means of bevel gears 7 to shaft 5 is a vertical transmission shaft 8 mounted in bearings 9 in the casting 2. The shaft 8 75 is in turn connected by a pair of bevel gears 10 to an upper horizontal shaft 11 mounted in bearings 12 on the casting 2. These shafts form the main driving connections for the machine.

80

Mounted on the end of the upper shaft 11 is a counter-weighted crank 13 connected by a pin 14 to a connecting rod 15 which, in turn is connected to a block 16 fixed to a needle bar 17 guided for vertical movement in suitable 85 bearings 18 in the head 3. It will be seen that operation of the shaft 11 will, through these connections, impart a vertically reciprocating movement to the needle bar 17.

90

Feeding mechanism

Mounted in bearings 19 in the casting 2 is a rock shaft 20. Adjustably mounted on the shaft 20 is a sleeve 21 provided with an upwardly extending arm 22 having formed 95 therein an arcuate slot 23. The sleeve 22 may be fixed to the shaft 20 in adjusted position by means of a set screw 24. Adjustably mounted on the shaft 5 is an eccentric 25 working in a collar 26 attached to a forward- 100

ly extending arm 27 pivoted at its ends to a block 28 slidably mounted in the slot 23 and adapted to be fixed in adjusted position therealong. These connections provide that the rotation of the shaft 5 will impart, through the agency of the eccentric 25, a rocking movement to the arm 22 which in turn will rock the shaft 20. The extent of such movement may be adjusted by adjusting the block 28 along the slot 23, and the timing of such movement may be adjusted by adjusting the eccentric 25 on the shaft 5.

The shaft 20 extends to the left in Figure 1 and has fixed thereto an upwardly extending arm 29. A U-shaped bridge 30 is shown interposed in the length of the shaft 20 in order to bridge a transversely extending shaft 31 whose purpose will be described later. The arm 29 is pivoted at its upper end to a feeding dog 32 having a toothed portion 33 adapted to engage the work in the usual manner. Rocking the shaft 20 will rock the arm 29 so as to impart a reciprocating movement to the feeding dog 32 as will presently be more fully described.

Loosely mounted on the shaft 20 is a sleeve 34 having an upwardly extending arm 35 provided with an arcuate slot similar to the slot 23. The shaft 5 carries a second eccentric 36 similar to the eccentric 25 and working in a collar 37 on an arm 38 similar to the arm 27 and similarly pivoted to a block 39, adjustable along the arm 35 in a manner similar to the adjustment of the block 28 along the arm 22. The sleeve 34 also has mounted thereon an upwardly extending arm 40 pivoted at its upper end to a pin 41 carrying a sleeve 42 mounted on the end of a feed control arm 43. These connections provide that the operation of the shaft 5 acting through the eccentric 36 and the arm 38 will rock the sleeve 34 which, through the agency of the arm 40 imparts a forward and rearward reciprocating movement to the arm 43. This reciprocating movement is part of the feeding movement.

The rearward end of the arm 43 is formed to provide a fork 44 adapted to embrace and provide a follower for an eccentric 45 also mounted on the shaft 5. The rearward end of the arm 43 also has mounted thereon a feeding dog 46 provided with a toothed upper surface in the usual manner. It will be seen that the cam 45 will impart to the arm 43 and the feeding dog 46 an up and down movement while at the same time the cam 36, acting through the connections just described, imparts a horizontal reciprocating movement to said dog. These movements are so coordinated by proper adjustments of the eccentrics that the feeding movement is given to the dog 46. The horizontal extent of such movement may be adjusted by adjusting the block 39 along the arm 35.

The sleeve 42 also carries a rearwardly ex-

tending arm 47 having an extension 48 upon which is mounted a block 49 adapted to slide in a slot 50 in the side of the dog 32. Thus the arm 47 and its extension 48 provide a support for the dog 32 which will impart to the latter an up and down movement corresponding to that of the arm 43. At the same time, the slot 50 permits a horizontal movement of the dog 32 relatively to the arm 43. As previously described, the extent of horizontal movement of the dog 32 may be adjusted by adjusting the block 28 along the arm 22. Accordingly, the horizontal movements of the dogs 46 and 32 may be independently adjusted and may have different extents. The adjustment is ordinarily made so that the dog 32 will have a greater horizontal movement than the dog 46. This is in order that when sewing knit goods, which is liable to stretch under the pull usually applied by the operator, this dog 32 will tend to gather or pucker the material under the needles. The result in fact is that the extra movement of the dog 32 simply compensates for the stretch of the goods applied by the operator.

Trimming mechanism

Shaft 11 carries an eccentric 51 working in a collar 52 on a link 53 which extends downwardly and is pivoted at 54 to one end of an arm 55, the other end of which is fixed to a rock shaft 56. The shaft 56 is journaled at 57 in a sleeve 58 supported in any suitable manner in the casting 2. The sleeve 58 has threaded thereto a plug which provides another bearing for the shaft 56. Within the sleeve 58 a coil spring 60 surrounds the shaft 56, bearing at one end against a collar 61 secured to the shaft and at the other end against the plug 59. The shaft 56 has fixed thereto at its end an arm 62, (see Fig. 3) which has adjustably mounted therein a trimming cutter 63. The operation of the shaft 11 causes the eccentric 51 to rock the shaft 56 so as to impart a vertical reciprocating movement to the cutter 63. This cutter has a bevel cutting edge as shown in Figs. 1 and 3 and bears against a corresponding stationary cutter 64. The cutter 64 is supported on an arm 65 supported in any suitable manner on a pedestal 66 on the base 1. These trimming cutters are so located with respect to the other mechanism that the superfluous material is trimmed from the edge of the work just before the same passes to the stitching mechanism.

Plain stitching mechanism

The needle bar 17 carries two needles 67 and 68. These needles are mounted vertically in the needle bar so as to move vertically therewith and are spaced at considerable distances apart from front to rear and are also

slightly displaced in a lateral direction. Both needles are provided with eyes 69 adapted to receive a thread in the usual manner.

5 Cooperating with the needle 67, which is located in advance of the other needle, stitching mechanism is provided adapted to sew a plain seam. This mechanism comprises a looper 70 mounted on and fixed to the shaft 31 running transversely of the base from front to rear just below the needles. This shaft has bearings in a sleeve 71 mounted in the pedestal 66 and a sleeve 72 having a bearing in a block 73 mounted on the base 1. The 10 shaft 31 is loosely mounted in these sleeves so as to be capable of both rotary and endwise movement therein. The sleeve 72 is also mounted for turning movement in the block 73 but is confined against endwise movement 15 by a pair of collars 74 fixed to the sleeve on opposite sides of the block 73. Secured to the sleeve 72 is a collar 75 having an arm 76 which carries at its end a pin 77 extending along the shaft 31 and passing through a 20 perforation in the looper 70 as will be seen from Fig. 7.

The shaft 5 carries, at an intermediate portion thereof, a spiral gear 78 adapted to mesh with a similar gear 79 on a transverse shaft 80, having bearings 81 on the base 1. (See Fig. 4.) The forward end of the shaft 80 carries a crank disc 82 which is connected by a link 83 to an arm 84 on the sleeve 75. It will be seen that rotation of the shaft 5 35 will cause rotation of the shaft 80 through the agency of the spiral gears 78 and 79 which in turn by means of the link 82 will rock the sleeve 72 so as to impart a corresponding movement to the looper 70.

40 The shaft 5 carries an eccentric 85 adapted to work in a fork 86 having an arm 87 attached to the shaft 31. This arm is attached by means of a collar 88 loosely fitting said shaft and confined by the collars 89 fixed to the shaft. The eccentric 85 is thus effective in imparting an endwise movement to the shaft 31 while at the same time permitting a rocking movement thereof to provide for rocking the looper 70.

50 The relation of the movement of the looper 70 to that of the needle 67 is such that the looper takes a loop from the needle after the latter has pierced the work, holding the loop as the needle is retracted and then shifting endwise of the shaft 31 to a position in front of the needle in a manner well known in the art for making a chain stitch seam. The needle 67 and its cooperating parts including the looper 70 therefore, provide stitching mechanism adapted to sew a plain seam which, in the present case, is of the chain stitch type.

Over-stitch mechanism

65 The needle 68 is adapted to cooperate with

stitching mechanism which will now be described to form an over-stitch covering the edge of the work.

The shaft 80 carries at its rearward end a second crank disc 90 whose crank pin 91 is connected by a link 92 to a pin 93 fixed to an arm 94 on a collar 95 fixed to a sleeve 96 mounted for a rocking movement in the pedestal 66. A rock shaft 97 has fixed thereto an arm 98 adapted to slide on the pin 93 as will be seen from Fig. 6. The shaft 97 has a bearing in the sleeve 96 so as to be both slideable and rotatable therein. It will be seen that by these connections rotation of the shaft 80 will impart a rocking movement to the shaft 97.

70 Mounted on the shaft 5 is an eccentric 99 working in a fork 100 which carries an arm 101 having lateral extensions 102 perforated to receive the shaft 97 on opposite sides of the arm 98 as shown in Fig. 6. The arm 98 being confined between the extensions 102 and said arm being fixed to the shaft 97, it will be seen that reciprocation of the fork 100 by the eccentric cam 99 will cause the shaft 97 to shift endwise in the sleeve 96. The shaft is thus given both a rocking movement by the link 92 and an endwise shift by the cam 99.

75 The sleeve 71 has fixed to the end thereof a looper 103. This looper is also perforated and the pin 77 (see Fig. 7) extends through said perforation in a manner similar to that described for the looper 70. The movement of the pin 77 will therefore cause a rocking movement to be imparted to the looper 103 as well as to the looper 70. The looper 103 is, however, secured against endwise shifting. While the looper 70 is positioned to cooperate with the needle 67, the looper 103 is correspondingly positioned to cooperate with the needle 68 but in a somewhat different manner as will presently be described.

80 Mounted on the end of the rock shaft 97 is a second looper 104. This looper has imparted to it a rocking movement and an endwise shifting movement as just described for the shaft 97. The needle 68, the looper 103 and the looper 104 cooperate to form the over-stitch seam as will now be described.

85 The movements of the needle 68 and the 113 loopers 103 and 104 are so coordinated as to form an over-stitch seam as follows, referring particularly to Figures 9, 10, and 11. The needle 68 descends, piercing the work represented at 105. As the needle is retracted a 120 loop is formed in the needle thread 106. The looper 103 which itself carries a thread 107, now advances and enters the loop in the needle thread, taking such loop from the needle as the latter retracts. The looper 103 retains 125 this loop and advances to its furthestmost position. Upon retraction of this looper a loop is formed in the thread 107 and the second looper 104 now rises and enters this loop, taking the same from the first looper 103 as 130

the latter retires. The looper 104 now rises, retaining its loop in the thread 107. As the looper 104 rises, due to the rocking movement of the shaft 97 imparted by the crank 90, it shifts forwardly at the same time in response to the action of the cam 99. The looper 104 now passes to the front of the needle 68 and passes over the edge of the work to a position adjacent the needle. This looper also carries a thread 108 which is carried upward therewith. The needle 68 now begins to descend for another stitch. In so doing it takes a loop in the thread 108 from the looper 104 which is then retracted. This sequence of operations is then repeated for successive stitches. It will be seen that the looper 103 carries its thread forwardly and the looper 104 after taking a loop from the first looper carries its thread up over the edge of the work to be caught in turn by the needle and stitched down on the upper side of the work. A succession of such stitches therefore forms a cover stitch extending over the edge of the work and binding the same against raveling and at the same time improving the appearance thereof.

As previously stated, the needle 67, forming the plain seam is spaced in advance of the needle 68 forming the over-stitch seam. At the same time the needle 67 is displaced laterally with respect to the other needle in such a direction that the plain seam formed by the first needle will be included and covered by the stitching formed by the second needle as will be seen from Figures 12 and 13.

In the operation of this machine the work is placed in the usual manner upon the cover plate or table 109 which is placed over the mechanism described above as shown in Figure 1. This plate is suitably perforated to accommodate the needles, the feed dogs and the trimming cutters. A presser foot 110 mounted on a bar 111 and controlled by a spring 112 is provided in the usual manner. The work having been placed upon the table and the machine started, the work will be fed forward by the operation of the feeding dogs. Just before arriving under the needles the rough edge of the work is trimmed off by the cutters 63 and 64. The work then passes under the needles, the needle 67 and its co-operating mechanism sewing a plain seam along the trimmed edge and at a fixed distance therefrom. The needle 68 and its co-operating mechanism thereafter adds an over-stitch seam which applies its stitching over the edge of the work and so as to include the plain seam. Thus the work is not only securely sewed together but the plain seam is also neatly bound by the cover stitch and these two functions are accomplished at a single operation of the machine.

It will be seen, therefore, that this invention provides a machine which is capable of sewing together such material as knit goods

with a plain seam and in addition with an over-stitch seam including the first seam, the material being neatly trimmed at its edge just prior to the stitching operation. The result is that a securely seamed and neatly finished article is produced. The entire operation including both seams is furthermore produced at a single operation. Consequently, a greatly increased rapidity of work may be carried out by this machine so that a much greater output may be obtained therewith.

It will be noted that the movements of all the loopers are accomplished by mechanism which involves only uniplanar movements, or movements which do not deviate from a single plane. Accordingly, the mechanism involves only pivotal connections and plain sliding movements. Such construction involves parts which are easily and simply manufactured with great accuracy, so that they may be made interchangeable. It is also clear that such movements provide for rigid support of the various parts so that this machine may be driven at a high speed without changing the accuracy of movements of the co-operating parts. Accordingly, the loopers will always co-operate accurately with the needles and with each other, and there will be no danger of dropping stitches or similar faults, even when operating at a high speed.

It is obvious that various changes may be made in details of construction without departing from the spirit of this invention. It is, therefore, to be understood that this invention is not to be limited to the specific details shown and described.

Having thus described the invention what is claimed is:

1. In a sewing machine, stitching mechanism including, a pair of vertically moving needles, a looper shaft, a pair of loopers mounted to turn about said shaft, one of said loopers being secured against endwise movement, means for turning said loopers about said shaft to take a loop from each of said needles, and means for shifting said shaft adapted to shift the other of said loopers transversely of its loop-taking movement.

2. In a sewing machine, stitching mechanism, comprising, a pair of vertically moving needles, a pair of loopers co-operating therewith, connections adapted to move said loopers to take a loop from each of said needles, a third looper cooperating with one of said first loopers to over-stitch the work, and means independent of said connections adapted to shift only one of said first loopers transversely of its loop-taking movement.

3. In a sewing machine, stitching mechanism, comprising, a pair of vertically moving needles, a pair of loopers co-operating therewith, connections adapted to move said loopers to take a loop from each of said needles, a third looper cooperating with one of said

first loopers to over-stitch the work, means independent of said connections adapted to shift one of said first loopers transversely of its loop-taking movement, and means adapted to secure said other looper against shifting.

4. In a sewing machine, stitching mechanism, comprising, a pair of vertically moving needles, a pair of loopers co-operating therewith, connections adapted to move said loopers in unison to take a loop from each of said needles, a third looper cooperating with one of said first loopers to over-stitch the work, and means independent of said connections adapted to shift only one of said first loopers transversely of its loop-taking movement.

5. In a sewing machine, stitching mechanism, comprising, a pair of vertically moving needles, a pair of loopers co-operating therewith, connections having only uniplanar movements adapted to move said loopers to take a loop from each of said needles, a third looper cooperating with one of said first loopers to over-stitch the work, and means independent of said connections adapted to slide one of said first loopers transversely of its loop-taking movement.

6. In a sewing machine, stitching mechanism, comprising, a pair of vertically moving needles, a pair of loopers co-operating therewith, means for mounting said loopers for movement to take a loop from each of said needles, means for moving said loopers together to take a loop from each of said needles, a third looper cooperating with one of said first loopers to over-stitch the work, and means operating through said mounting means adapted to shift only one of said first loopers transversely of its loop-taking movement.

7. In a sewing machine, looper mechanism, comprising, a bearing, a sleeve rotatably mounted therein, a shaft movable in said sleeve, a looper on said sleeve, and a looper on said shaft.

8. In a sewing machine, looper mechanism, comprising, a bearing, a sleeve rotatably mounted therein, a shaft movable in said sleeve, a looper on said sleeve, a looper on said shaft, and means for moving said shaft independently of said sleeve.

9. In a sewing machine, looper mechanism, comprising, a bearing, a sleeve rotatably mounted therein, a shaft movable in said sleeve, a looper on said sleeve, a looper on said shaft, means for turning said loopers about said shaft, and means for moving said shaft endwise.

10. In a sewing machine, looper mechanism, comprising, a bearing, a sleeve rotatably mounted therein, a shaft movable in said sleeve, a looper on said sleeve, a looper on said shaft, an element engaging said loopers and movable to turn said loopers about said

shaft, and means for moving said shaft endwise.

In testimony whereof I affix my signature this 11th day of September, 1925.
